UNITED STATES PATENT OFFICE.

WILLIAM H. SOMMER, OF PEORIA, ILLINOIS, ASSIGNOR, BY MESNE ASSIGNMENTS, TO THE FIRST TRUST & SAVINGS COMPANY, OF CLEVELAND, OHIO, A CORPORATION OF OHIO, AND WILLIAM E. STONE, OF PEORIA, ILLINOIS, TRUSTEES.

WIRE-HEADING MACHINE.

1,287,777.

Specification of Letters Patent. Patented Dec. 17, 1918.

Application filed July 10, 1916. Serial No. 108,336.

To all whom it may concern:

Be it known that I, WILLIAM H. SOMMER, a citizen of the United States, residing at Peoria, in the county of Peoria and State of Illinois, have invented new and useful Improvements in Wire-Heading Machines, of which the following is a specification.

This invention has reference to wire heading machines, and it has for one of its objects to provide a machine for heading the ends of the wires in a gate frame to secure the wires thereto. Such a gate with wires attached thereto by a heading process are shown in patents granted to me on June 3, 1913, No. 1,063,223, and one on October 19, 1915, No. 1,157,054.

The invention has for a further object to provide a means for supporting and advancing a gate frame in a step-by-step movement through the machine to align the wire openings in the gate frame with the feeding mechanism, whereby the wires to be attached to the frame may be fed through the openings therein, preparatory to the heading process.

The invention has for a further object to provide a wire feeding mechanism and tripping means engaged by the wire for setting in motion the timing shaft and the mechanism to be actuated thereby for gripping one end of the wire, forming a head thereon, retracting the feed wire, severing or cutting a length of wire from the feed wire, gripping the unheaded end of the wire and heading the same.

The invention has for a further object to cold-head one end of the wire or wires and to hot-head the other end of such wire or wires.

A further object of the invention is to provide an interchangeable feeding mechanism for the gate frame whereby said frame may be advanced in a step-by-step movement at uniform distances or at graduated distances with each movement.

For a further and full description of the invention herein and the merits thereof and also to acquire a knowledge of the details of construction of the means for effecting the result, reference is had to the following 50 description and drawings hereto attached.

While the essential and characteristic features of the invention are susceptible of modification, still the preferred embodiment of the invention is illustrated in the 55 accompanying drawings.

Figures 1 and 2, taken together, show a front elevation of the machine, parts in section, the wire feeding mechanism being in operation threading a wire through the gate frame, the parts being in the position just prior to the wire engaging the tripping mechanism which sets the timing shaft in operation;

Figs. 3 and 4, taken together, show a plan view of what is shown in Figs. 1 and 2, the parts being in the same position;

Figs. 5 and 6, taken together, show a rear elevation of the machine, parts in section, with the parts in the same position as they appear in Figs. 1, 2, 3, and 4;

Fig. 7 is a front elevation similar to Fig. 2, with parts broken away and other parts in section, and shows the mechanism for retracting the wire drawn back, the section of wire threaded through the gate frame severed from the feed wire stock, and the means for forming the hot-head on the end of the wire in the act of forming such head;

Fig. 8 is an end elevation of the machine looking at the left-hand end of Fig. 1, and with parts of the machine broken away;

Fig. 9 is an end elevation of the machine looking at the right-hand end of Fig. 2, with parts broken away;

Fig. 10 is a vertical cross section as the same would appear if taken on the line 10—10 of Fig. 2, looking in the direction of the arrow on said last-mentioned figure;

Fig. 11 is a vertical cross section as the same would appear if taken on the line 11—11 of Fig. 2, looking in the direction of the arrow on said last-mentioned figure;

Fig. 12 is a vertical cross section as the same would appear if taken on the line 12—12 of Fig. 2, looking in the direction of the arrow on said last-mentioned figure;

Fig. 13 is a detail elevation of mechanism shown in Fig. 1, parts being in section for the purpose of illustrating the manner of gripping and clamping the end of the feed wire and forming the cold-head thereon, and the cold-heading mechanism;

Fig. 14 is a vertical cross section as the same would appear if taken on line 14—14 of Fig. 2, and illustrates the mechanism for releasing the feed gripping means for the feed wire immediately after the formation of the cold-head on the end of the wire;

Fig. 15 is a face view of what is shown in Fig. 14;

Fig. 16 is a detail partially in cross section showing the jaw for gripping the wire for the formation of the hot head, and the mechanism for actuating said jaw, this jaw also serving as a guide for the threading of the wire through the frame;

Fig. 17 is a fore-shortened elevation of the mechanism which sets the timing shaft in motion, such mechanism being actuated by the feed wire;

Fig. 18 is a detail sectional view in plan showing the mechanism which is actuated by the feed wire for setting in motion the mechanism shown in Fig. 17, and which in turn sets in motion the timing shaft, the parts being in the position just previous to the tripping operation by the feed wire;

Fig. 19 is a perspective view showing the mechanism which interrupts the movement 20 of the driving shaft just at the time when the hot head is being formed on the wire;

Fig. 20 is a vertical cross section, parts being broken away, as the same would appear if taken on the line 20—20 of Fig. 2, this view illustrating the mechanism for advancing the gate frame in the machine in a step-by-step movement, the wires being spaced at uniform distances apart;

Fig. 21 is a view similar to Fig. 20 except that the feeding means for the frame for advancing it in a step-by-step movement through the machine has been changed so as to feed the frame in a step-by-step movement at graduated distances;

Fig. 22 is a cross section as the same would appear if taken on the line 22—22 of Fig. 21;

Fig. 23 is a plan view showing a wire having been threaded through the top and bottom, or horizontal reach bars of the gate frame, uncut from the stock, with the free ends of the wire about to be cold headed;

Fig. 24 is a view similar to Fig. 23, except that the wire stock has been withdrawn, the headed end of the wire brought firmly against the frame, the headed wire severed from the stock, the filler wire clamped within the gate frame, and the free end of said wire with the hot head thereon just about completed;

Fig. 25 is a view showing that the filler wires extending in one direction through the gate frame constituting what are known as the stay wires, have been placed and headed, and cross wire threaded therethrough, and that the same is in the same stage of the operation as the wire is in in Fig. 23;

Fig. 26 is a view similar to Fig. 25 except that the cross wire is at the same stage of the operation, as the wire is in, in Fig. 24;

Fig. 27 is a diagrammatic view to show the wiring for the hot header;

Fig. 28 is a detail side elevation of the mechanism for clamping the gate frame in a

fixed position during the heading of the wires, being that mechanism located at the hot heading side of the machine, the clamp being in a raised position;

Fig. 29 is a front elevation of the parts 70 shown in Fig. 28;

Fig. 30 is a side elevation of the means for clamping the gate frame in a fixed position at the cold heading side of the machine, the clamping means being in a raised position;

Fig. 31 is a view of a gate with the strand and stay wires secured therein by being headed on my machine, the intersections of said stay and strand wires being connected 80 by staples, not shown, put on by a separate machine forming the subject matter of an application filed by me on January 17th, 1916, bearing Serial No. 72,619, for improvements in wire filler securing means for gate 85 frames.

In Fig. 31 I have shown a gate frame comprising the top and bottom bars T and T' and the opposite end bars U and U'. The top bar and the opposite end bars of the 90 gate frame are preferably bent into form from a single piece of tubing, the ends of the opposite end bars being mitered as shown. The bottom bar T' of the gate is also preferably made of tubing, its ends mitered and 95 the same welded to the mitered ends of the opposite end bars of said frame. The top and bottom bars T and T' are provided with oppositely disposed perforations or openings to receive the wires which are 100 threaded therethrough and which form the stay or picket wires of the gate. The opposite end bars U and U' are likewise provided with perforations or openings to receive wires which are threaded therethrough and 105 which serve as the longitudinal strand or line wires of the gate.

In Figs. 3 and 4 and also in Figs. 23 and 24, the gate frame is in a position in the machine with the wires being threaded 110 through the top and bottom bars of the gate frame, such wires constituting the stay wires of the gate.

In Figs. 25 and 26 the gate frame has been turned around and the wires are being 115 threaded through the opposite end bars of the gate, which said wires serve as the longitudinal strand or line wires.

Like characters of reference denote corresponding parts throughout the figures.

In the manufacture of wire gates, that is, gates made of tubular frame parts, and with a wire filler, the ends of the wires have been usually connected to the bars of the frame by being wrapped thereabout and twisted 125 with the body of the wire. Gates so manufactured, have been largely made by hand, although in some cases machines are used for this purpose. If made by hand, difficulty has been experienced in stretching the 130

wires taut so as to make a firm filler within the frame; and whether made by hand or by machine it has been the custom to only secure the ends of the longitudinal wires of the filler to the end vertical bars of the gate frame, and the top and bottom marginal wires of the filler have been sustained by short connections of wire between said marginal wires and the top and bottom bars 10 of the frame.

It is the object of the present invention to provide a wire filler for gate frames having not only the ends of the longitudinal strand wires connected to the opposite or 15 vertical end bars of the frame, but also to have the opposite ends of the stay or picket wires connected to the top and bottom or horizontal bars of the gate frame; such longitudinal and vertical stay wires being connected to the frame before their intersections are united, the uniting of the intersections of said wires being made in a separate machine constructed for this purpose, so that when the wire filler has been secured 20 within the gate frame it forms practically a unitary part thereof and not only strengthens the frame, but is so connected as to prevent the wires slipping upon the frame or becoming slack under pressure there- 25 against. Instead of connecting the ends of the longitudinal and stay or picket wires to the gate frame by wrapping the same thereabout and twisting the ends of the wires with their bodies, I prefer to pass the 30 ends of each and all of the wires constituting the filler through openings in the vertical end bars and also openings in the horizontal or top and bottom bars and heading the ends of such wires; one end of each 35 of said wires being preferably cold-headed and their opposite ends being preferably hot-headed.

From the foregoing statement, it is obvious that under the old practice of attaching 40 a wire filler to a gate frame that the wire filler has been a section taken from a piece of wire fabric, the same being laid across the frame and the ends only of the longitudinal wires wrapped about the vertical end 45 bars of the gate frame. With the present invention I do away with the idea of taking a section from a piece of fence fabric, but rather connect separate wire sections to the gate frame to constitute the longitudinal, 50 and stay or picket wires, and as stated, the intersections of such wires are connected by other means, and in a separate machine forming the subject matter of a co-pending application.

55 In the manufacture of gates having a wire filler, the stay or picket wires have a uniform spacing, but the longitudinal or strand wire in most if not all cases have a graduated spacing, such graduated spacing of the 60 longitudinal strand wires and the uniform

spacing of the stay or picket wires conforming to the spacing of similar wires in the fence fabric with which the gate frames are associated. Therefore, it is necessary to provide a machine by which not only the 70 stay wires may be attached to the frame with a uniform spacing, but that the longitudinal strand wires may be attached to the frame with a graduated spacing. In practice, the machine would be adjusted for putting in the stay wires with a uniform spacing until a quantity of gates had been made, when the mechanism would be changed or 75 adjusted so that the longitudinal strand wires might be attached to the frame with a graduated spacing. The present application embodies both structures. However, a manufacturer making a large number of gates would have two machines of substantially similar construction, in one of which 80 the mechanism would be adjusted to put in all of the stay wires, and in the other of which the mechanism would be adjusted to put in all of the longitudinal strand wires, 85 and in this way avoid the necessity and loss of time in changing the mechanism whereby uniform spacing of certain of the wires may be made, and graduated spacing of the other wires may be made. It is also understood that gates vary in size both in height 90 and in length, and the mechanism for attaching the wires must be adjustable to provide for this change in size of the gates.

The frame supporting the bearings for the working parts of the machine is of considerable length, and for convenience in the assembling of the machine and for the removal of parts therefrom, I have made the frame in several sections, designated 1, 2 and 3, the same being suitably detachably connected to each other. On the frame parts 1 and 2 is journaled the driving or power shaft 4, and on the frame parts 2 and 3 is journaled the timing shaft 5. On the frame part 2 is mounted the means for actuating the mechanism for feeding the gate frame through the machine in a step-by-step movement; the mechanism for clamping that side of the gate frame on which the wires are hot headed; the wire feeding and wire retracting 100 mechanism; the mechanism for severing the sections of wire from the stock; the hot heading mechanism, and other detailed parts to be more specifically described. On the frame part 3 is mounted for longitudinal adjustment a supplemental frame, upon which is mounted the mechanism for clamping that side of the frame on which the wires are cold headed; the tripping mechanism actuated by wires as they are threaded 110 through the gate frame, for setting in motion the timing shaft of the machine, and other detailed parts to be more specifically described. The supplemental frame being 120 adjustable for the purpose of adapting the 130

working parts of the machine to different heights and lengths of gate frames.

On the driving shaft 4 is loosely carried a driving pulley 6, said pulley adapted to be driven by a belt from a line shaft or other suitable power.

The hub of this pulley is provided with a clutch face 7, and adapted to have a clutch relation therewith is a clutch part 8 formed 10 on one end of a sleeve 9, said sleeve having spline and groove connection with the shaft 4, whereby it may be moved endwise on the shaft and to impart rotation thereto when the clutch parts 7 and 8 are in the clutch 15 gaging relation shown in Fig. 2. Said sleeve 9 at its opposite end is formed with, or has connected thereto, a cam wheel 10, for purposes which will be further explained, see Fig. 6, and said sleeve, adjacent the 20 clutch part 8, is formed with, or has connected thereto, a grooved collar 11, and operating in the groove of the collar are diametrically opposed studs or pins connected with the bifurcated end of a lever 12 25 through and by means of which the sleeve 9 may be moved longitudinally on the shaft 4 to connect the clutch part 8 with the clutch part 7 on the pulley 6, or for the purpose of separating said clutch parts. On the inner 30 end of the driving shaft 4 is carried a bevel gear wheel 13 and on said shaft in the rear of said bevel gear wheel 13 is a spur pinion 14. The bevel gear wheel 13 meshes with a bevel gear wheel 15 carried on the lower 35 end of a shaft 16, while the spur pinion 14 meshes with a large spur gear wheel 17 carried on the timing shaft 5. The gear wheel 17 is loosely carried on the timing shaft 5 and the hub of said gear wheel is formed 40 with a clutch part 19 adapted to have engagement with a clutch part 20 formed on one end of a sleeve 21 having a spline and groove connection with the timing shaft 5, whereby the sleeve 21 may be moved endwise 45 on the timing shaft and adapted to impart rotation to said timing shaft when the clutch part 20 of said sleeve is in clutch engaging relation with the clutch part 19 of the gear wheel 17.

50 The shaft 16, driven by the bevel gear wheel 15 from the driving shaft 4, is journaled in fixed bearings on the frame part 2, and on this shaft is carried a gear wheel 22 having the friction feed wheel 23. Meshing 55 with the gear wheel 22 is a gear wheel 24 carried upon a short shaft 25 journaled in arms 26 pivoted at 27 to a bracket 28 secured on the frame part 2, said gear wheel 24 having the friction feed wheel 29 which 60 co-operates with the friction feeding wheel 23 on the shaft 16 to feed the wire threaded through the gate frame. The arms 26 in which is journaled the gear wheel 24 and the friction feeding wheel 29, are adapted 65 to have slight oscillatory movement to re-

lease the friction feeding wheel 29 from contact with the wire, or to cause the same to impinge therewith to co-operate with the companion feeding wheel for projecting the wire to be threaded through the gate frame. 70 The movement of the arms 26 to release the friction feeding wheel 29 from the wire will not be sufficient to separate the teeth of the gear wheel 24 from the teeth of the gear wheel 22, said gear wheels always remaining 75 in mesh whether the feeding wheels impinge upon the wire or not.

Means is provided to enable the operator of the machine to control the feeding of the wire by the friction feed rollers 23 and 29, 80 and means is also provided whereby the arms 26 are moved automatically to release the friction feed wheel 29 from impinging relation with the wire to stop the feeding thereof, at a proper time in the operation 85 of the machine and in timed relation to the means for heading the wire. The means permitting the operator to control the operation of the friction feed wheel 29 upon the wire, comprises a stem 30 connected 90 with the outer ends of the arms 26, said stem extending through and having a bearing in a bracket 31 and on the outer end of said stem 30 which projects through the bracket 31, is secured an operator's lever 32 95 having a cam engaging surface 33, see Figs. 4 and 14. On the stem 30 between the arms 26 and the bracket 31 is carried a coil spring 34. When the operator's lever 32 is swung down in the direction shown by the arrow 100 in Fig. 14, the cam surface 33 then bearing against the bracket 31 will permit the coil spring 34 to expand, moving the arms 26 in a direction which will cause the friction feeding wheel 29 to impinge upon the wire 105 and in co-operation with the friction feeding wheel 23 will feed the wire forward; the raising of the operator's lever 32 in the opposite direction from that indicated by the arrow in Fig. 14 will cause the cam surface 110 33 on the said lever to ride on the bracket 31, drawing the arms 26 outwardly, looking at Fig. 4, compressing the spring 34 and releasing the friction feeding wheel 29 from impinging or feeding relation with the wire. 115 Therefore, when the operator moves the lever 32 downwardly, the friction feeding wheels 23 and 29 will operate upon the wire to feed the same, and when said lever is moved upwardly, the feeding operation is 120 discontinued.

To impart movement from the driving shaft 4 to the feeding shaft 16, the clutch part 8 must be in clutch relation with the clutch part 7 of the driving pulley 6 125 and to move said clutch part 8 through the lever 12, said lever at its upper end has adjustably connected thereto a rod 35 which has a pivotal connection with the inner end of operator's lever 36, see Figs. 4 and 6, 130

said operator's lever extending forwardly of the machine and resting upon an arm or support 37, see Fig. 4, said operator's lever 36 being pivoted at a suitable point intermediate its ends (not shown), whereby reciprocal movement may be imparted to the rod 35 and in turn oscillate the said lever 12 which is pivoted at 38 to an arm or support 39, see Fig. 2. A spring 40 connected to the upper part of the lever 12 and also to the frame will normally hold the clutch part 8 in clutch engaging relation with the clutch part 7 of the driving pulley 6, but the clutch part 8 may be held disengaged from the clutch part 7 by throwing the lever to the left, looking at Fig. 4, and locking the same against the lug 41 on the arm or rest 37, as will be understood.

It is readily apparent from the foregoing how the clutch part 8 may be controlled by the operator causing the same to engage with clutch part 7 or be disengaged therefrom, and also the manner in which the friction feeding wheel 29 may be controlled by the operator for causing it to impinge upon the wire and in coöperation with the feeding wheel 23 to feed the wire, or to be moved from impinging relation with the wire. For the automatic release of the friction feeding wheel 29 from the wire and at a proper time in the operation of the machine preparatory to the heading operation upon the wire, I employ the mechanism which is best seen in Fig. 14, for this purpose. Pivotedly connected to the arms 26 is an arm 42 of a toggle lever, the other arm 43 of said toggle lever having a bearing in a frame part of the machine, and said toggle lever is connected with a rod 44 having reciprocal movement through a guide 45 and said rod 44 at its lower end carries a roller 46 which rides on the peripheral surface of a cam wheel 47 carried on the timing shaft 5. When the friction feeding wheels 23 and 29 are in impinging relation upon the wire, feeding the same to thread a wire through the gate frame, the roller 46 will ride in the depression 48 on the cam wheel 47 and said roller 46 will leave the depression on the cam wheel just at the time when the feeding of the wire should be stopped, and said roller riding up onto the surface of the cam wheel 47 forming the larger circumferential surface of said wheel, will raise the rod 44, operating the toggle lever so as to move the arms 26 outwardly a very slight distance and move the friction feeding wheel 29 from impinging relation with the wire. Regardless of the position of the cam wheel 47 with its depression 48, the operator may control the position of the friction feeding wheel 29 through the operator's lever 32, as will be understood.

The wire fed by the friction feeding wheels 23 and 29 and which forms the

filler for the gate frame, is designated A. This wire is drawn from a bundle, or a reel, or a spool, and passes first under and over the set of straightening rollers 49, see Figs. 4 and 9, and thence between the series of straightening rollers 50, see Figs. 4 and 7, each and all of said straightening rollers 49 and 50 being mounted upon a plate 51 which has a slideable connection upon a bed plate portion 52 of the frame part 2. The wire A leaving the straightening rollers 50, passes between the friction feeding wheels 23 and 29, which said wheels may be circumferentially grooved or not, as may be desired, and from the feeding wheels the wire passes through aligned guiding parts 53 and 54, the latter being longitudinally movable in guides 55, and the outer end of the guiding part 54 comprises hinged sections 56 which are adapted to open and spread apart over the guide 53 when the guide 54 is retracted or moved in the direction of the friction feeding wheels, as shown in Fig. 7, and to close when returned to their normal guiding position shown in Fig. 2. The retractable movement of the guide 54 is for the purpose of moving the forward end of said guide from the position shown in Fig. 2 to allow the hot header to move into position for heading the severed wire section in the gate frame, without interference, as will be more fully explained. The plate 51 is moved backward from the position shown in Figs. 2 and 4 to the position shown in Fig. 7 for the purpose of withdrawing the wire stock after the formation of the cold head, as will be further explained, and bringing the cold head into engagement with the gate frame and to make the wire taut, before the severance of the wire section in the gate frame from the wire stock, and just preceding the hot heading of the wire section, the straightening rollers 49 and 50 gripping the wire sufficiently to withdraw the wire during the outward movement of the plate 50. The plate 51 is moved outward to the position shown in Fig. 7 and returned to the position shown in Figs. 2 and 4 by means of links 57 which have a pivotal connection with the plate 51 and which also have a pivotal connection with a lever 58 pivoted at 59 to a part of the frame part 2, and the lower end of said lever 58 has a roller 60 which travels on the cam surfaces of a cam wheel 61. The cam surfaces on the wheel 61 which control the movement of the lever 58, are designated a, b, c, d, e, and f, see Fig. 2. When the roller 60, carried by the lever 58, is traveling over the cam surface a from the surface f to the surface b, the plate 51 is moved from the outward position shown in Fig. 7 to the position shown in Figs. 2 and 4, and during the travel of the roller 60 over the cam sur-

face *b*, the plate 51 and the guiding rollers 49 and 50 are retained in the inward position shown in Figs. 2 and 4, during which time the wire stock A is fed forward and threaded through the gate frame. When said roller 60 is moving over the cam surface *c* the plate 51 is moved slightly outwardly, which results in the withdrawing of the wire stock A, after the cold heading operation, to bring the head into engagement with the gate frame and to make the wire taut, and during the travel of the roller 60 over the cam surface *d*, the wire section in the gate frame is severed from the wire stock, as will be more fully explained, and during the travel of the roller 60 over the cam surface *e*, the plate 51 is further retracted to withdraw the wire stock A so as to move the forward free end thereof from a position which would interfere with the operation of the hot header, as shown in Fig. 7, and during such last retraction of the wire stock the guide 54 for the stock will be retracted or withdrawn from that position shown in Fig. 2 to the position shown in Fig. 7 so as to remove the forward end of the guide 54 from interference with the action of the hot header upon the severed section of the wire in the gate frame. During the action of the hot header, as will be explained, the timing shaft is interrupted in its movement which covers a very short period of time, when the operation of the timing shaft is resumed, which will cause the roller 60 to travel over the surface *f* of the cam wheel 61, and during this time the hot header is returned to its inoperative position and the gate frame is advanced to a position for the threading of the wire stock therethrough, and at approximately the same time the guide 54 is moved to its foremost position shown in Fig. 2, and the plate 51 with the straightening rollers is also returned to permit the forward feeding of the wire stock A and the threading of the same through the gate frame. To retract and return the guide 54 to the position shown in Fig. 7 and Fig. 2, there is pivotally connected with said guide a link 62 which also has a pivotal connection with the upper end of a lever 63 pivoted at 64 to the frame part 2, and the other end of said lever 63 has a pivotal connection with a vertically movable slide bar 65 on the lower end of which is a roller 66 riding upon a cam surface 67, on the cam wheel 47 previously referred to. It is therefore obvious that when the slide bar 65 is lowered, the guide 54 is retracted or moved to that position shown in Fig. 7, and when said bar 65 is elevated it will return the guide 54 to the operative position shown in Fig. 2. Connected at one end to the guide 54 is a spring 68, the opposite end of which

is connected to the frame part 2. The normal action of this spring is to retract the guide 54, said spring being expanded under the action of the cam 67, moving the guide 54 to its normal outward, operative position. A similar spring 69 has one end connected to a frame part and its opposite end to a post 70 connected with the plate 51 upon which is mounted the straightening rollers 49 and 50. The normal action of the spring 69, is to hold the plate 51 in its forward or operative position, said spring being expanded by the outward movement of the plate 51, as shown in Fig. 7.

I provide a series of guides for the wire stock which are located on the machine within the confines of the gate frame, when the gate frame is in position for the wire stock A to be threaded therethrough. One of such guides is designated 71 and the remaining guides are designated 72, the guide 71 also serving as a clamp to grip the wire adjacent that side of the gate frame on which the hot head is formed. The guides 71 and 72 are substantially the same in construction and are operated substantially in the same way, and are best seen in Figs. 1, 2, 4 and 16. A description will be given of the combined guide and clamp 71, which is the one shown in Fig. 16, and the description of this will suffice for a description of the other guides 72, the differences being pointed out between the two where such differences may exist. 73 designates the fixed part of the guide suitably supported upon a frame part of the machine, the guiding portion thereof formed with a groove 74. The movable part of the guide is designated 75 and is pivoted to the fixed part at 76, and said movable part also has a groove 77 which cooperates with the groove 74 of the fixed part to form a passageway for the wire stock A through the guide. Passing through the lower end of the movable part 75 of the guide is a rod 78, said rod extending to the rear of the machine, passing through a frame part and connected at its outer end to the upper end of a crank arm 79 carried on a rock-shaft 80. Encircled on the rod 78 is a spring 81 disposed between the lower end of the movable part 75 and a washer and nut carried on the rod 78. It is understood from the foregoing that each guide comprises a fixed and a movable part, corresponding to the parts 73 and 75, and that there is a rod and spring connection between each movable part and the rock-shaft 80, as shown in Fig. 16. There is a difference in the tension of the springs 81 for the guides 71 and the guides 72; that is to say, the spring 81 for the guide and clamp 71 has a stronger tension than the springs 81 for the remaining guides 72, for purposes which will be explained. On the

outer end of the rock-shaft 80 is carried a crank arm 82 having a roller 83 adapted to bear and ride upon a peripheral cam surface of cam wheel 84 carried on the corresponding outer end of the timing shaft 5, see Figs. 1, 3, 8 and 16. To hold the roller 83 in constant engagement with the peripheral cam surface of said cam wheel 84, a spring 85 is provided having one end connected to a frame part, as at 86, see Figs. 9 and 20, and its opposite end connected to one of the crank arms 79 carried on the rock-shaft 80. The movement of the rock-shaft 80 through the crank arm 82 is against the tension of this spring 85, which, as is apparent, will hold the roller 83 against the cam surfaces of said cam wheel 84. The cam wheel 84 is provided with the peripheral cam surfaces *g*, *h*, *i*, *j* and *k*. When the roller 83 carried by the crank arm 82 is riding on the cam surface *g*, the rock-shaft 80 is rocked so as to permit the springs 81 on the rods 78 to contract and move the movable parts 75 of the guides to a position where the grooves 74 and 77 of said fixed and movable parts of the guides will complete a passageway across the machine within the confines of the gate frame to guide the wire stock A as the same is threaded through the gate frame. It is to be understood that the springs 81 acting upon the movable parts 75 of the guides 72 will be contracted and exert their full force upon such movable parts when the roller 83 is traveling over the cam surface *g*, but this is not true of the spring 81 which acts upon the movable parts 75 of the guide 71, as such spring does not exert its full force until the roller travels upon the cam surface *h*. When the roller 83 leaves the cam surface *g* and rides on to the cam surface *h*, the movement of the rock-shaft 80 further contracts the spring 81 and allows the spring 81 to exert its full force, moving the movable part 75 of the combined guide and clamp 71 to cause it to clamp upon the wire, firmly gripping the same between the gripping surfaces of said movable part 75 and said fixed part 73 of this particular guide; such movement of the rock-shaft not affecting the other guides 72, for the reason that the springs 81 are much weaker and will not act upon their movable parts of the guides to clamp the same upon the wire, having exerted their full force during the time the roller 83 is traveling upon the cam surface *g*, as just previously stated. The combined guide and clamp 71, as will be observed from an examination of the drawings, particularly Fig. 4, is located within the confines of the gate frame, adjacent to that side of the gate frame on which the hot heads of the wires are formed, the hot head on the severed section of the wire being made just before the roller 83 leaves the cam surface *h* to ride onto the cam surface *i*, and the clamping of the wire by the combined guide and clamp 71 is to hold the wire firmly at this end during the formation of the hot head. After the formation of the hot head which completes the attaching of the wire section within the gate frame, the roller 83 moves onto the cam surface *i* of said cam wheel 84, the roller being forced into the deepest depression of the surface *i* through the action of the spring 85 which will rock the shaft 80 so as to reciprocate the rods 78, oscillating the movable parts 75 of the guides 71 and 72, whereby the attached section of the wire in the gate frame may be moved away and out of said guides during the time the gate frame is being advanced to a position for the threading of another wire therethrough, the gate frame being advanced to a new position, during the time that the roller 83 is traveling over the cam surface *j*, the movable parts 75 of the guides 71 and 72 being returned to a partially closed position during the time the roller 83 is traveling over the cam surface *k* from the cam surface *j* to the cam surface *g*.

The end of the feed wire A after being threaded through the gate frame and the guides 71 and 72, will engage with the head 87 on one end of a plunger 88 having a bearing and reciprocally carried in a slideable block 89; such engagement of the end of the wire with the head 87 will move the plunger 88, causing it by engagement with the lever 90 to oscillate the same against the tension of a spring 91. The oscillation of this lever 90 will release the end 92 of said lever from engagement with a shoulder 93 on a rod or bar 94 reciprocally carried in bearings 95, said bar or rod 94 coupled to a rod 96 through a coupling 97, see Figs. 5 and 18. The plunger 88 preferably engages with an adjustable set screw or equivalent device 98 connected with the lever 90, the adjustment of said set screw or equivalent device 98 shortening or lengthening the movement of the plunger 88 before said lever will be actuated. The spring 91 which engages with the outer end of the lever 90, normally retains said lever in position to be engaged by the plunger 88 and to engage with the shoulder 93 on the bar or rod 94, when said bar or rod has been moved to the position shown in Fig. 18. The block 89 is adapted, through mechanism to be described, to actuate the plunger 88 and its head 87 to form the cold head on the end of the feed wire A. The rod 96 extends approximately the full length of the machine, and is disposed on the rear side thereof, being best seen in Figs. 5, 6 and 17, the forward end thereof, (being that end at the in-feed side of the machine), is pivotally connected at 99 with a bar 100 which at its forward end has a pivotal connection with the upper end of a

bell-crank lever 101 pivoted at 102, the opposite end of said bell-crank lever having a pivotal connection with the upper end of a rod or plunger 103 reciprocally carried in a housing 104. The opposite or rear end of said rod 96 passes through and has an adjustable connection with a comparatively thin bar 105 connected with a crank arm 106 which is pivotally connected at 107 to a support 108. The lower end of the bar 105 is formed with a slightly hooked end 109, see Figs. 1 and 17. The bar 105 is positioned at that end, see Fig. 16, of the machine at which the cam wheel 84 is located and said cam wheel 84 on its rear face is provided with a lug or projection 110 which is adapted during the rotation of the cam wheel 84 to bear against the bar 105 and to place a tension thereon for the operation of the rod 96 to actuate the rod or plunger 103 for the purpose of releasing it from parts which control the operation of the timing shaft 5 through the gear wheel 17 and the clutch parts 19 and 20, see Fig. 6, previously described. The rod or plunger 103 normally engages with a flange 111 formed on one end of the sleeve 21, to hold said sleeve in a retracted position against the tension of a spring 112 on the timing shaft 5, separating the clutch part 20 on the sleeve 21 from the clutch part 19 on the hub of the gear wheel 17. When the parts are in this position, the timing shaft 5 is at rest. To release the rod or plunger 103 from the flange 111 to allow the spring 112 to move the sleeve 21 to cause a clutch engagement of the clutch part 20 with the clutch part 19 on the hub of the gear wheel 17, the lug or projection 110 on the cam wheel 84 is in substantially that position in which it is shown in Fig. 17, having been moved to that position during an operation of the timing shaft, placing a tension on the bar 105, whereby when the lever 90, see Fig. 18, is moved through the operation of the plunger 88 by the engagement of the end of the wire with the head 87 on the end of said plunger, releasing the end 92 of the lever 90 from the shoulder 93 on the bar or rod 94, the tension upon the bar 105 will reciprocate the rod 96 in the direction indicated by the arrow in Fig. 17, oscillating the bell-crank lever 101, raising the rod or plunger 103, releasing it from engagement with the face of the flange 111 on the sleeve 21, permitting the spring 112 on the timing shaft 5 to expand, moving the clutch part 20 of said sleeve 21 into clutch engagement with the clutch part 19 on the hub of the gear wheel 17, imparting rotation to the timing shaft 5 through transmission of power from the driving shaft 4 through the pinion 14 of said gear wheel 17, the timing shaft continuing its operation, with the exception of a slight interruption thereof during the hot heading operation, as will be described, until the flange 111 on the sleeve 21 is rotated to a position which will bring a cam slot 113 in the face of said flange coincident with said rod or plunger 103, when the said rod or plunger will be caused to enter the same through the action of a spring 114, the rod or plunger moving out of said cam slot 113 against the face of the flange, during which movement the sleeve 21 is retracted against the tension of the spring 112, separating the clutch parts 19 and 20, and stopping the operation of the timing shaft 5. Not only does the action of the spring 114 insure the rod or plunger 103 entering the cam slot 113 in the flange 111 so as to separate the clutch parts 20 and 19, but such action of said spring will also reciprocate the rod 96 in a direction opposite to that indicated by the arrow in Fig. 17, moving said rod 96 and the rod or bar 94 through the coupling 97 to a position which will permit the end 92 of the lever 90 to engage with the shoulder 93 on said bar or rod 94, substantially as shown in Fig. 18, the lever 90 being actuated so that it may be locked against the shoulder 93, by means of the spring 91, as previously explained. During the operation of the timing shaft 5, the bar 105 engaged by the lug or projection 110 on the cam 84, is inactive, said cam rotating and bringing the lug or projection 110 to a position which will place a tension upon said bar 105 when the same has been reciprocated to the position where it is locked, substantially as shown in Fig. 18.

Immediately upon the tripping of the mechanism, just described, through the engagement of the end of the wire A with the head 87 on the plunger 88 for imparting rotation to the timing shaft from the driving shaft, the timing shaft 5 will operate the mechanism which moves the plunger 88 so as to form a cold head on the end of said wire A, the wire being first gripped between clamping members, which are also actuated by the operation of said timing shaft. The mechanism for clamping the end of the wire A to be cold headed, and said cold heading mechanism will now be described.

The supplemental frame, previously referred to, and upon which is mounted the mechanism for clamping the end of the wire A when it is cold headed, and on which is also mounted the cold heading mechanism, is designated 115 and is best seen in Figs. 1 and 5. This supplemental frame is adjustably mounted on the frame part 3, having a dove-tailed relation therewith, the frame part 3 being provided for a portion of its length with a rack bar 116, see Fig. 1, and meshing with said rack-bar is a gear wheel 117, shown in dotted lines in Fig. 1, carried on a transverse shaft 118 journaled in suit-

able bearings in said supplemental frame 115. To operate the shaft 118 to adjust the supplemental frame 115 when it is desired, a removable operator's bar 119 is used, the 5 same being inserted into any one of a series of radially disposed perforations 120 provided in a sleeve or collar 121 secured on said shaft 118, and the shaft is rotated until the supplemental frame is adjusted to the 10 desired position.

The mechanism for gripping the end of the wire stock A for clamping it in a fixed position during the cold heading operation, comprises the pair of clamping bars 122 15 slidably disposed in a head 123 forming a part of or attached to the supplemental frame 115. These clamping or gripping bars are actuated by means of a pair of levers 124, each journaled at 125 in a suitable manner on said supplemental frame 115. On the outer end of each lever 124 is journaled a roller 126 adapted to ride on the cam surface of a cam wheel 127. The roller 126 of the lower lever 124 is held in engagement with the cam surface of its cam wheel 127 by means of a spring 128, one end of which is connected to said lower lever 124 and the other end of said spring is connected with a part of said supplemental frame 115, 20 see Figs. 1 and 13. The roller 126 of the upper lever 124 is held in engagement with the cam surface of its cam wheel 127 by gravity. The cam wheels 127 are carried in spaced relation above and below each other 25 on a shaft 129, said shaft being driven from the timing shaft 5 by means of a bevel gear 130 carried on the lower end of the shaft 129 which meshes with and is driven by a bevel gear wheel 131 carried on the timing shaft 5, 30 see Figs. 1 and 13. Connected with the inner or shorter end of each of said levers 124 is a spring 132, the opposite end of which is connected with a clamping or gripping bar 122. These springs serve to move the clamping or gripping bars 122 in opposite directions to release the wire stock A when the rollers 126 of the levers 124 move over the lowest point or shallow portion of said cam wheels 127. To move the gripping or clamping 35 bars 122 toward each other for the purpose of causing the same to firmly grip and hold the wire stock A during the cold heading operation, I provide an adjustable set screw 133 connected with the inner end of 40 each of said levers 124, and the ends of these set screws fit in sockets 134 in the outer ends of short pins or rods 135, the opposite ends of which fit in sockets 136 in the outer ends of the gripping or clamping bars 122, see 45 Fig. 13. This form of flexible joint or connection between the levers 124 and the clamping or gripping bars 122 is made because of the vertical motion which is transmitted to the clamping or gripping bars 122 through 50 the oscillating movement of the levers 124.

To cold head the end of the wire stock A immediately after the end of said wire has been clamped between the clamping and gripping bars 122, the plunger 88 must be forcibly moved to cause its head 87 to engage with and cold head the end of the wire stock A. The plunger is so moved by means of the block 89 in which it is journaled, said block having pivotally connected thereto one end of a crank arm or connecting rod 137, 55 the opposite end of which is connected eccentrically with the shaft 129 on which the cams 127 are carried. Immediately upon the formation of the cold head, the cams 127 rotate to a position which will move the levers 124 60 so as to release the clamping or gripping blocks 122 from the wire stock A and permit the stock to be drawn backward, bringing the cold head on the end of the wire against the bar of the gate frame at that side of the 65 machine. The withdrawing of the wire stock A is accomplished in the manner previously described by means of the cam wheel 61, the lever 58, and plate 51 on which are carried the guiding and straightening rollers. 70

The wire stock A having been cold headed and the stock withdrawn, in the manner previously described, bringing the cold head up against the bar of the gate frame, the wire section having the cold head is severed from 75 the wire stock, whereby the ends of said wire section may be hot headed. However, before said section of the wire is severed from the wire stock A, said wire is firmly clamped within the gate frame by means of 80 the guide and clamp 71, said guide and clamp 71 being actuated as previously described, by means of the cam 84 on the timing shaft 5 and the crank arm and connections with said clamp, as described. The 85 wire section is severed from the wire stock by means of shears comprising the co-acting parts 138 and 139 pivoted to each other at 90 140, the jaws of which have connected thereto the knife portions or cutters 141 and 142, 95 said cutters provided with cutting portions which, when the wire section is severed, leaves the end of the wire stock A pointed, thus facilitating the easy threading of the 100 wire through the bars of the gate frame 115 when said wire is projected forward for this purpose. On the lower end of each of said 105 parts 138 and 139 of the cutting shears, see Fig. 7, is journaled a roller 143, the roller 110 on the part 138 adapted because of its position to ride over the cam surface 144 of the cam wheel 145, and the roller on the part 139 is caused through the action of a spring 143' to ride over the cam surface 146 of said 115 cam wheel 145, the cam wheel 145 being 120 carried upon and operated by the timing shaft 5. Immediately after the severance of the wire section for the gate from the 125 wire stock A, the cam wheel 61, as previously described, will actuate the lever 58 to 130

- move the plate 51 farther backward so as to withdraw the end of the wire stock A from a position which might interfere with the action of the hot header upon the end of 5 the wire section in the gate, and at or about the time of this further backward movement of said plate 51 to retract the wire stock, the guide 54 for the wire stock between the feeding wheels and the gate frame will be retracted or withdrawn, in the manner previously described, from that position shown in Fig. 2 to the position shown in Fig. 7 so as to remove the forward end of the guide 54 from interference with the action of the 10 hot header upon the severed section of the wire in the gate frame.

The hot header designated 147 is carried by an arm 148 secured to the upper end of a rock shaft 149, said shaft journaled in 20 suitable bearings on the frame part 2. Secured to said rock shaft intermediate its ends and adjustable thereon is an arm 150 having a roller 151, said roller adapted to ride on the surface of a cam wheel 152 secured to and operated by the timing shaft 5, said cam wheel having the cam surface or depression 153. Also secured to the rock shaft 149, preferably above the arm 150, is an arm 154 and connected with the outer 25 end of said last mentioned arm is an adjustable set screw 155 which is adapted to engage with an arm 156 loosely carried on the rock shaft 149 above said arm 154, and passing through the outer end of said arm 30 35 40 45 50 55 60 65

156 is a rod 157, said rod on its end adjacent said arm 156 provided with adjusting nuts 158, and said rod at its opposite end pivotally connected with the upper end of a lever 159, said lever being fulcrumed at 160 to a bracket 162 secured to the frame part 2, best seen in Fig. 6. The lever 159 has an angular portion 163 adapted to bear against and ride on the outside face of the cam wheel 61, previously described as being carried on the timing shaft, and best seen in Figs. 2, 7 and 9, and during the rotation of said cam wheel 61 the angular portion 163 of said lever 159 will enter a slot or cam depression 164 provided in the face of said cam wheel 61 near its periphery, as best seen in Fig. 9. Said lever 159 is also provided with a right angular extension or arm 165 having a bifurcated end which straddles a vertically disposed rod 166 movable and having a bearing 55 60 65 70 75 80 85 90 95 100 105 110 115 120 125 130

55 60 65 70 75 80 85 90 95 100 105 110 115 120 125 130

ing in the bracket 162. This rod 166 is provided with a collar 167 located just beneath the bifurcated portion of the arm 165 of the lever 159, and on said rod between said collar and one of the bearings for said rod is carried a spring 168 the purpose of which is to exert pressure to lift the rod 166 simultaneously with the entrance of the angular portion 163 of the lever 159 into the slot or cam depression 164 of said cam wheel 61.

Secured on said rock shaft 149 at or near

its lower end are a pair of collar arms 169 and 170. To the collar 169 is secured one end of a coil spring 171, the opposite end of which is connected to the frame part 2, see Fig. 2, and to the collar 170 is connected one 70 end of a rod 172 which at its opposite end is connected with a plunger or piston 173 operating in the chamber of a fluid tank or box 174. This fluid tank or box 174 is preferably filled with oil, serving to retard the 75 movement of the rock shaft 149 under the action of the spring 171 during the hot heading process in a manner which I shall now explain.

Assuming that the wire section in the 80 gate frame has been clamped, severed from the wire stock A, the stock withdrawn and the guide 54 moved out of the way to permit the hot header to perform its functions, and the timing shaft 5 being rotated in manner explained, the spring 171 will hold the rock shaft 149 in a position which will cause the roller 151 of the arm 150 to bear against and ride on the surface of the cam wheel 152 which is rotated with the timing shaft 5. 85 At or about the time the cam surface or depression 153 in the cam wheel 152 is brought coincident with the roller 151, the cam wheel 61 on the end of said timing shaft 5 will have reached a position where the slot or 90 cam depression 164 in the face of said cam wheel 61 will coincide with the angular portion 163 of the lever 159. As this slot or cam depression 164 coincides with the angular portion of said lever 159, said angular 100 portion of the lever will be caused to enter said slot or cam depression 164 through the action of the spring 168 on the rod 166, lifting said rod and with it the arm 165 of the lever 159, forcing the angular portion 163 105 of said lever into said slot or cam depression 164, reciprocating the rod 157, bringing the adjusting nuts thereon in juxtaposition to the end of the arm 156 through which said rod 157 passes. When the foregoing operation takes place the collar 10 on the sleeve 9 on the driving shaft 4 has reached a position where the cam slot 175 thereof will be brought coincident with said rod 166, permitting said rod to enter said cam slot, and 110 as the driving shaft 4 continues to rotate the rod 166 will slide the sleeve 9 on the driving shaft 4 so as to cause a separation of the clutch part 8 on said sleeve from the clutch part 7 on the driving pulley 6, stopping or 115 interrupting the rotation of the timing shaft 5. This movement of the sleeve 9 to cause a separation of the clutch parts 8 and 7 is against the tension of the spring 40 connected with the lever 12, previously described. As was stated above, the angular portion 163 of the lever 159 is caused to enter the slot or cam depression 164 in the face of the cam wheel 61 at or about the time the roller 151 on the arm 150 carried by the 120 125 130

rock shaft 49 enters the cam depression 153 in the cam wheel 152 which is brought to this position through the rotation of the timing shaft 5, said roller 151 being caused 5 to ride into said depression 153 in said cam wheel through the action of the spring 171. That the roller 151 may not enter the depression 153 in the cam wheel 152 with a sudden movement, I provide the fluid regulating means comprising the cylinder 174 with the plunger or piston operating therein, the same being connected to the rock shaft 149 in the manner described, the plunger operating against the fluid, which 10 15 will retard the movement of said rock shaft while yet allowing it to be partially rotated for the purpose of bringing the hot head 147 against the end of the wire section under the action of the spring 171 for the purpose of forming the hot head on the end of the wire section in the manner best seen in Figs. 23 to 26, both inclusive. At the instant that the roller 151 enters the depression 153 in the cam wheel 152, the clutch parts 8 and 20 25 29 30 35 40 45 50 55 60 65 70 75 80 85 90 95 100 105 110 115 120 125 130 135 140 145 150 155 160 165 170 175 180 185 190 195 198 200 202 204 206 208 210 212 214 216 218 220 222 224 226 228 230 232 234 236 238 240 242 244 246 248 250 252 254 256 258 260 262 264 266 268 270 272 274 276 278 generated by the current passing through the hot header. The controller D is connected by lead S with the knife switch H.

Reference being had to Fig. 27, we will assume that the knife switch H is closed, that the arm of the controller D is in contact with a button of one of the lead wires R with the coils of the transformer for the proper proportioning of the amount of heat desired for the heating of the electrode 147, in order that the same may properly heat by heating the end of the wire section in the gate frame. At or about the time that the electrode 147 is moved in the manner previously described to cause the same to engage with the wire section in the gate frame, the rotary switch or safety device I has been moved by the timing shaft 5 so as to close the circuit between the wires or conduit O' and P, and at or about this time or at that instant, when the electrode 147 is brought into contact with the end of the wire section in the gate frame, the sleeve 9 on the driving shaft 4 is moved through the operation of the lever 159 and the rod 166, separating the clutch part 8 on the sleeve 9 from the clutch part 7 on the pulley 6, the movement of the sleeve moving the plunger M, suitably connected therewith, which will engage with the spring plate L of the circuit breaker, causing it to make contact with the contact point K of said circuit breaker and complete the circuit between the wire or conduit P, the circuit breaker and the wire or conduit Q connected with the coils of the transformer. Thus it will be seen that with the electrode 147 in contact with the wire section in the gate frame, said wire section passing through the gate frame which rests upon the part F forming the negative electrode, the current will pass from the transformer through the lead E, to the electrode 147, thence to the electrode F, heating the wire section in the gate frame for the purpose of heating the same, and thence through the lead G back to the transformer and from the transformer through the controller and the wire or conduit S, through the knife switch H and back to the source of supply.

Although I have not shown the manner of connecting the plunger M with the sleeve 9, this plunger passes into the driving shaft 4 and is connected by a transverse pin with the sleeve 9, said pin operating in a slot in the shaft. This, as will be understood, will allow the plunger to be reciprocated through the reciprocation of the sleeve 9 when the same is disengaged and engaged with the hub of the driving pulley 6.

I will now describe the manner of supporting and feeding the gate frame through the machine whereby a plurality of wire sections may be threaded therethrough, and cold and hot headed on their opposite ends

as described, the description being directed at first to the mechanism which will feed the gate frame at uniform distances with each movement, and then subsequently the means will be described which will feed the gate frame at graduated distances with each movement of the frame. This, as has been stated, is for the purpose of threading the gate frame with stay wires which are placed at uniform distances apart and the feeding of the longitudinal or strand wires which are placed at graduated distances apart. This uniform and graduated feeding mechanism, as stated, may be employed on a single machine, the one being substituted for the other when it is desired to thread the gate frame with wires at graduated distances apart. However, as stated, in the manufacture of gate frames it is preferable to have two machines of substantially like character except that one is provided with means for feeding the gate through the machine at uniform distances with each movement, and the other is provided with means for feeding the gate through the machine at graduated distances with each movement. In this way the cost of production is considerably lessened and the number of gates manufactured is greatly increased during the same amount of time.

176 and 177 denote frame parts, the former being secured to the frame part 2 and the latter being secured to the movable supplemental frame part 115. These frame parts 176 and 177 have extensions forward and rearwardly of the machine, see Figs. 3, 4, 9, 20 and 21. Mounted upon and extending longitudinally of the frame parts 176 and 177 are the beams 178, preferably I-beams, each of which are provided with longitudinally arranged inverted rack bars 179. The beams 178 are movable in grooves or channels 180 in the upper faces of the frame parts 176 and 177 and operatively retained in these channels by means of plates 181 secured to the frame parts 176 and 177 and overlying the lower flanges of said beams 178. Meshing with the rack bars 179 on the beams 178 are gear wheels 182, the same being mounted upon a supplemental shaft 183 journaled in suitable bearings at its forward end on the frame part 2, and at its opposite ends in suitable bearings on the supplemental frame part 115. The gear wheel 182 on that end of the supplemental shaft 183 which is journaled in bearings on the supplemental frame part 115, is provided with a grooved sleeve 184 and engaging said grooved sleeve is an arm 185 secured to bearings for said shaft on the supplemental frame 115, whereby the gear wheel 182 just mentioned may be moved on the supplemental shaft 183 during any adjustment of the supplemental frame 115 on the frame part 3, for purposes previously

explained. On the forward end of the said supplemental shaft 183, see Figs. 2 and 20, are carried the larger ratchet toothed wheel 186 and smaller ratchet toothed wheel 187. Adapted to engage with the teeth on the ratchet toothed wheel 186 is a pawl 188 pivotally connected with one end of a lever 189 fulcrumed on said supplemental shaft 183 and on its opposite end carrying a roller 190 adapted to ride upon the surface of a cam wheel 191 carried upon and operated by the timing shaft 5, see Fig. 26. The pawl 188 is yieldingly retained in a position for engagement with the teeth of the ratchet toothed wheel 186 by means of the spring 192, see Fig. 20, one end of which is attached to the pawl 188 and the other end of which is attached to the lever 189. Carried by the said supplemental shaft 183 and movable thereabout is a lever 193, said lever having a detent or pawl 194 spring held from engagement with the teeth of the ratchet toothed wheel 187, and said detent or pawl is connected with a rod 195 which in turn is connected with an operator's finger 195' pivotally connected with the outer end of the lever 193. The detent or pawl 194 is normally held from engagement with the teeth on the ratchet toothed wheel 187 and may be moved into engagement therewith by the operation of the finger 195' on the lever 193, and when so engaged upon the oscillation of the lever 193 the operator may advance or move backward beams 178 through the intermeshing of the gear wheels 182 with the rack bars 179 on said beams. It is obvious that to move the beams 178 backward, the pawl 188 will of necessity have to be released from engagement with the teeth of the ratchet toothed wheel 186. The real purpose of the ratchet toothed wheel 187 and the lever 193 with its detent or pawl adapted to engage with the teeth of the ratchet toothed wheel 187, is to move the beams 178 with the gate frame thereon to a position preliminary to the threading of the wire through the first perforations in the gate frame through which it is intended to thread the first wire, thereafter, the lever 189 and the pawl 188 are adapted through the operation of the timing shaft 5 and cam 191 to move the beams 178 in a step by step movement to advance the gate frame through the machine for the proper threading of wires therethrough. In Fig. 20 the teeth of the ratchet wheel 186 are of uniform length, each tooth being preferably two inches in length. Assuming now that the wires in the gate frame are to be threaded at uniform distances, or say for example, six inches apart, each movement of the lever 189 for the purpose of moving the beams 178 will be sufficient to move the pawl 188 the distance of three teeth of the ratchet toothed wheel 186, re-

sulting in the movement of the gate frame six inches through the machine, the distance between the wires to be threaded therethrough.

The gate frame is supported on the beams 178 in the manner best seen in Figs. 3, 4, 9, 20 and 21, the forward and rear end bars of the gate frame being clamped in position on the beams 178 by means of the forward and rear clamping members 196 and 197. The forward clamps 196 have connected thereto threaded stems 198 which pass through blocks 199 forming a part of or attached to plates 200 adapted to be adjustably secured to the beams 178. On the said stems 198 between the clamps 196 and blocks 199, coil springs 201 are carried. When the clamps 196 are adjusted in correct position to receive the gate frame, by means of said stems 198 being threaded, they may be released from said gate frame by withdrawing the threaded stems in the blocks 199 releasing the clamps 196 from the gate frame, the said threaded stems being retained in adjusted positions by means of the nuts 202 on said stems. The clamps 197 are in most respects similar to the clamps 196; that is to say, they are connected with threaded stems 198' which are adjustable in blocks 199' forming a part of or attached to plates 200' secured to the beams 178. The difference between the clamps 196 and 197 is that the former may be moved from clamping engagement with the gate frame to permit the gate frame to be released from the clamps 197 and taken from the machine. When a gate frame is adjusted in operative position, the clamps 196 and 197 are so positioned as to engage the opposite end bars of the frame, in the manner seen, retaining the gate frame in an operative clamped position on the beams 178 to be adjusted therewith through the operation of the supplemental shaft 182. The plates 200 are adapted to be adjusted in like manner on the beams 178 as the plates 200', this is for the purpose of attaching the clamps to different size gate frames upon the beams 178. The clamping means just previously described, as is obvious, has reference to the means for clamping the gate frame upon the beams to provide for the movement of the gate frame through the machine during the operation of the supplemental shaft 182. In addition to this clamping means, I also provide on opposite sides of the machine means for frictionally clamping the opposite bars of the gate frame, which, while the same will permit the gate frame to be moved through the action of the supplemental shaft 182 and connections with the rack bars 179, will retard the frame against any sudden or jerky movement, and control it so that the movement of the gate frame will be gradual and uniform. Without such means the mo-

mentum of the shaft 183 when it is in operation might have a tendency to rotate slightly farther than desirable and require a readjustment of the gate frame for the proper 5 threading of the wires therethrough. This clamping means for retarding the movement of the gate frame may be seen in Figs. 1, 2, 3, 4, 5, 6, but best seen in Figs. 28, 29 and 30. Extending longitudinally of the machine 10 and journaled in suitable bearings on the frame part 2 and the supplemental movable frame part 115 is a rock shaft 203. On the end of the said rock shaft 203 at the in-feed side of the machine for the wire stock A is 15 secured a lever 204 and secured to said rock shaft at or near its opposite end is an arm 205. The lever 204 is operatively carried through a slot 206 in a vertically movable bar 207 on the lower end of which is secured 20 a friction clamping member 208 adapted to have a friction engaging relation with one of the bars of the gate frame. The bar 207 is reciprocally carried in upper and lower bearings 209, and 210 of a frame 211 secured 25 to the frame part 2 of the machine. The lever 204 when in its elevated position shown in Fig. 28, is adapted to be locked in that position with the bar 207 raised, by means of a stem 212, and when the lever 204 is 30 lowered moving with it the bar 207 to cause the part 208 of said bar to frictionally engage with a bar of the gate frame, the lever is locked in said lowermost position by means 35 of a locking stem 213. These stems 212 and 213 have a bearing in the frame 211, each of said stems having thereon the springs 214, which serve to keep the stems in their outermost positions shown in Fig. 29. The outer ends of said stems 212 and 213 may be 40 projected or withdrawn in the frame 211 for the purpose of locking the lever 204 in the position shown in Fig. 8 or to allow the lever to be raised or lowered. The opposite ends of said stems 212 and 213 are connected 45 to crank arms 215, see Fig. 9, projecting radially from hubs 216 carried on a rock shaft 217, said shaft being journaled in bearings on the frame 211 and said shaft is adapted to be rocked in its bearings by means of the 50 lever 218. It is now obvious that if it is desired to lower the lever 204 from the inoperative position shown in Fig. 28 to the operative position shown in Fig. 9, the rock shaft 217 is rotated in its bearings which would 55 release the stems 212 and 213, allowing the lever to be lowered, the same being locked below stem 213 in the same manner in which it is now locked above the stem 212 in the raised position shown in Fig. 28.

60 On the in-feed side of the machine for the wire stock A, as has been stated, is carried the lever 204, this lever acting directly upon the means for frictionally clamping the gate frame at that side of the machine. The 65 operation of this lever will also operate the

shaft 203 which carries at or near its opposite end the arm 205, and when said lever is lowered from that position shown in Fig. 28 to the position shown in Fig. 9, it will raise the arm 205, releasing said arm from engagement with the spring arm fulcrumed at 220 on the movable frame part 215, the rear end of said spring arm 219 being drawn upward by the contraction of the spring 221 connected thereto and to a bar 222, causing the forward or opposite end of said spring arm 219 to yieldingly bear and have an impinging relation against a bar of the gate frame. The spring 221 will hold the spring arm 219 in yielding engagement with a bar 8 of the gate frame, and a spring 223 which is carried on the bar 207 between the lower bearing 209 and an offset on said bar, will yieldingly hold this bar against any sudden action downward when the stems 212 and 213 are drawn back or released. The engaging end of the bar 207 and bar 219 with opposite bars of the gate frame is in axial alignment with the threading of the wires therethrough and yieldingly clamps the frame in line with the mechanism for cold and hot heading the sections of the wires in said frame, and serve to prevent any upward movement of the frame at this point during the threading of the wires through the gate frame and the heading of the same.

Reference being had to Fig. 21, the modified mechanism is shown which is substituted for the mechanism shown in Fig. 20 when it is desired to advance the gate frame 1 in the machine in a step-by-step manner at graduated distances. The only change from the mechanism shown in Fig. 20 with that shown in Fig. 21 is the substitution of a ratchet toothed wheel 224 having square 11 toothed ratchets which are spaced at graduated distances around the periphery instead of the radial ratchet teeth spaced at uniform distances on the periphery of the ratchet toothed wheel 186 shown in Fig. 20. Assuming that the pawl 188 is engaging a tooth of the ratchet toothed wheel 224, Fig. 21, and the cam wheel 191 rotates to return the pawl 188 to a position to engage another tooth with said ratchet toothed wheel 224, 11 said pawl will ride over a finger 225 shown in dotted lines in said Fig. 21, which will remove the pawl from the tooth of the ratchet wheel and allow it to ride on the peripheral surface of said wheel and continue to ride until it coincides with the next succeeding tooth of the ratchet toothed wheel 224, when the spring 192 will act to draw the pawl into said tooth. This will hold the lever 189 in a position above the peripheral surface of the cam 191 until the cam engages with the roller 190 on the lever 189 to oscillate said lever and move the ratchet toothed wheel 224 its distance to 12 advance the gate frame the proper distance 13

in the machine. The lever 189 is yieldingly held with its roller 190 in the direction of the peripheral surface of the cam wheel 191 by means of a light tension spring 226. The 5 object of the spring is to overcome the friction between the lever and the shaft 183 on which it is journaled, and to insure the roller 190 riding on the peripheral surface of the cam wheel 191.

10 It is obvious, although not very clearly shown, that the forward parts of the frames 176 and 177 and the lower flanges on one side of the beams 178 will have to be cut away, as shown in dotted lines in Fig. 20, 15 to allow the gear wheels 182 to mesh with the rack bars 179.

I have provided a tripping mechanism for stopping the operation of the supplemental shaft 183 after the hot heading of 20 the last wire section in the gate frame. This mechanism is best seen in Figs. 4, 7, 11, 20 and 21, and includes a pin 227 suitably attached to a plate 228 which may be a part of or attached to the adjustable plate 200^a, 25 or suitably connected direct to the beam 178. The pin 227 upon the completion of the hot heading process, the beam 178 having moved forwardly, will engage with the upper end of a crank arm 229 carried on one end of 30 a rock shaft 230, see Figs. 9 and 11, and attached to the other end of said rock shaft is a crank arm 229^a, to the lower end of which is connected a rod 231 the opposite 35 end of which is formed with a hooked end 232. The engagement of the pin 227 with the crank arm 229 will rock the shaft 230 and with it the crank arm 229, moving the rod 231 forwardly causing its hooked end 232 to move under and engage a pin 233 40 journaled in the lever 189 on which is carried the roller 190 adapted to ride on the surface of the cam wheel 191. The engagement of the hooked end 232 of the rod 231 takes place at a time just preceding the 45 lowering of the roller end of the lever 189, and prevents it from so moving, and thereby holds the roller 190 from contact with the cam surface of the cam wheel 191, stopping the movement of the supplemental shaft 183.

50 Upon the return of the beams 178 to their initial position to receive another gate frame, the crank arm 229 will be released and a spring 234 will rock the shaft 230 to return the rod 231 connected thereto to the inoperative position shown in Fig. 11.

What I claim is:

1. In a machine of the character described, in combination, means for supporting a gate frame, mechanism for threading wires through the frame, and mechanism for heading the opposite ends of the wires to secure the same in the frame.
2. In a machine of the character described, in combination, means for supporting a gate frame, mechanism for threading

wires through the frame, means for cold heading one end of each of said wires, and other means for hot heading the opposite end of each of said wires, to secure the same in the frame.

70

3. In a machine of the character described, in combination, means for supporting a gate frame, mechanism for threading wire stock through the frame, means for heading the end of the wire stock, means for 75 retracting the wire stock to bring the formed head on the end thereof against the gate frame, means for severing a wire section from the wire stock, and means for heading the other end of said wire section, to 80 secure the same in the frame.

4. In a machine of the character described, in combination, means for threading wire stock through the frame, means for clamping the end of said wire stock, means 85 for heading the end of said wire stock, means for retracting the wire stock to bring the formed head on the end thereof against the gate frame, means for severing a wire section from the wire stock, means for 90 clamping the end of said wire section, and means for heading the end of said wire section, to secure the same in the frame.

5. In a machine of the character described, in combination, means for supporting a gate frame, mechanism for threading wire stock through the frame, means for cold-heading the end of the wire stock, means for retracting the wire stock to bring 95 the formed head on the end thereof against the gate frame, means for severing a wire section from the wire stock, and means for hot-heading the end of said wire section, to 100 secure the same in the frame.

6. In a machine of the character described, in combination, means for supporting a gate frame, mechanism for threading wire stock through the frame, means for cold-heading the end of the wire stock, means for retracting the wire stock to bring 110 the formed head on the end thereof against the gate frame, said wire-retracting means having an intermittent movement, means for severing a wire section from the wire 115 stock during an interval of rest of said wire-retracting means, said wire-retracting means operating to further retract said wire stock after the severance of a wire section therefrom, and means for hot-heading the end of said wire section, to secure the same in the 120 frame.

7. In a machine of the character described, in combination, a support for a gate frame, said frame having openings therethrough for the passage of wires, mechanism for threading wires through the openings in said gate frame, mechanism for intermittently moving said support to present the openings in the gate frame in position for the threading of wires therethrough,

125

130

and mechanism for heading the opposite ends of the wires to secure the same in the frame.

8. In a machine of the character described, in combination, a support for a gate frame, said frame having openings therethrough for the passage of wires, means for clamping said gate frame on said support, mechanism for threading wires through the openings in said gate frame, mechanism for intermittently moving said support to present the openings in the gate frame in position for the threading of wires therethrough, and mechanism for heading the opposite ends of the wires to secure the same in the frame.

9. In a machine of the character described, in combination, a support for a gate frame, said frame having openings therethrough for the passage of wires, means for clamping said gate frame on said support, yielding gripping means for holding the gate frame to its work, mechanism for threading wires through the openings in said gate frame, mechanism for intermittently moving said support to present the openings in the gate frame in position for the threading of wires therethrough, and mechanism for heading the opposite ends of the wires to secure the same in the frame.

10. In a machine of the character described, in combination, a support for a gate frame, said frame having openings therethrough for the passage of wires, mechanism for threading wires through the openings in said gate frame, mechanism for intermittently moving said support to present the openings in the gate frame in position for the threading of wires therethrough, means for cold heading one end of each of said wires, and other means for hot heading the opposite ends of each of said wires, to secure the same to the frame.

11. In a machine of the character described, in combination, a support for a gate frame, said frame having openings therethrough for the passage of wires, means for clamping said gate frame on said support, mechanism for threading wires through the openings in said gate frame, mechanism for intermittently moving said support to present the openings in the gate frame in position for the threading of wires therethrough, means for cold heading one end of each of said wires, and other means for hot heading the opposite ends of each of said wires, to secure the same in the frame.

12. In a machine of the character described, in combination, means for supporting a gate frame, mechanism for threading wires through the frame, means for cold heading one end of each of said wires, and electrically heated means for hot heading the opposite end of each of said wires, to secure the same in the frame.

13. In a machine of the character described, in combination, a support for a gate frame, said frame having openings therethrough for the passage of wires, mechanism for threading wires through the openings in said gate frame, means for clamping the opposite ends of said wires, a plunger for cold heading one end of each of said wires, means for operating said plunger, and electrically heated means for heading the opposite ends of each of said wires.

14. In a machine of the character described, in combination, means for supporting a gate frame, mechanism for threading wire stock through the frame, means for clamping the free end of said wire stock, a plunger for cold heading one end of each of said wires, means for operating said plunger, means for retracting the wire stock to bring the formed head on the end thereof against the gate frame, means for severing a wire section from the wire stock, means for clamping the severed end of said wire section, and electrically heated means for heading said severed end of said wire section, to secure the section of wire in the gate frame.

15. In a machine of the character described, in combination, a support for a gate frame, said frame having openings therethrough for the passage of wires, mechanism for threading wires through the openings in said gate frame, gearing for moving said support, and means for intermittently operating said gearing to move said support so as to present the openings in the gate frame in position for the threading of wires therethrough, and mechanism for heading the opposite ends of the wires to secure the same in the frame.

16. In a machine of the character described, in combination, a support for a gate frame, said frame having openings therethrough for the passage of wires, mechanism for threading wires through the openings in said gate frame, a ratchet and pawl mechanism for advancing said support in a step by step movement to present the openings in the gate frame in position for the threading of wires therethrough, mechanism for heading the opposite ends of the wires to secure the same in the frame, and a tripping mechanism adapted to interfere with the operation of said ratchet and pawl mechanism upon the completion of the threading of the wires through said gate frame.

17. In a machine of the character described, in combination, a support for a gate frame, said frame having openings therethrough for the passage of wires, mechanism for threading wires through the openings in said gate frame, manually operated means for preliminarily advancing said support and said gate frame to a position for the threading of a wire through the gate frame, other mechanism for intermittently moving

said support to present the openings in the gate frame in position for the threading of wires therethrough, and mechanism for heading the opposite ends of the wires to secure 5 the same in the frame.

18. In a machine of the character described, in combination, a support for a gate frame, said frame having openings therethrough for the passage of wires, mechanism 10 for threading wires through the openings in said gate frame, manually operated means for preliminarily advancing said support and said gate frame to a position for the threading of a wire through the gate frame, 15 other mechanism for intermittently moving said support, including a ratchet and pawl, means for operating said pawl, mechanism for heading the opposite ends of the wires to secure the same in the frame, and means for 20 tripping said pawl upon the completion of the threading of the wires through said gate frame.

19. In a machine of the character described, in combination, a support for a gate 25 frame, mechanism for intermittently moving said support to advance the gate frame through the machine, mechanism for feeding wire stock through the machine and across the gate frame, means for severing 30 sections of wire from said wire stock, and means for connecting the opposite severed ends of said wire sections to oppositely disposed bars of said gate frame.

20. In a machine of the character described, in combination, a support for a gate 5 frame, mechanism for advancing said gate frame through the machine in a step-by-step movement, mechanism for feeding wire stock across the gate frame, means for severing 10 sections of wire from said wire stock, and mechanism for suitably forming the opposite ends of said wire sections to secure the same to the gate frame.

21. In a machine of the character described, in combination, a support for a gate frame, mechanism for advancing said gate frame through the machine in a step-by-step movement, mechanism for feeding wire stock across the gate frame, means for severing 15 sections of wire from said wire stock, means for first forming the end of the wire stock to prevent its displacement from the frame, and other means for subsequently forming the severed ends of the sections of wire to prevent their displacement from the frame.

22. In a machine of the character described, in combination, a support for a gate frame, mechanism for feeding wire stock across said frame, means for severing a section of wire from said wire stock, to be attached to the frame, a suitable mechanism for first forming one end of said wire section to prevent its displacement from the frame, and other mechanism for forming the

opposite end of said wire section to prevent its displacement from the frame.

23. In a machine of the character described, in combination, a support for a gate frame, mechanism for feeding wire stock 70 across said frame, means for severing a section of wire from said wire stock to be attached to the frame, mechanism adapted to operate upon the end of the wire stock prior to the severance of a section of wire therefrom for forming the end of the wire stock to prevent its displacement from the frame, and other mechanism adapted to operate upon the end of the section of wire subsequently to its being severed from the wire stock for forming the end thereof in a manner to prevent its displacement from the frame.

24. In a machine of the character described, in combination, a support for a gate frame, mechanism for feeding wire stock across said frame, means for gripping the end of the wire stock, means for forming the gripped end of the wire stock in a manner which will prevent its displacement 90 from the frame, means for severing a section of wire from the wire stock, means for gripping the severed end of said wire section, and means for forming the gripped and severed end of said wire section in a 95 manner which will prevent its displacement from the frame.

25. In a machine of the character described, in combination, a support for a gate frame, mechanism for feeding cross wires to 100 be attached to said frame, mechanism for operating upon one end of each of said wires in a manner which will prevent their displacement from the frame, and other and different mechanism for operating upon the 105 opposite ends of each of said wires in a manner which will prevent their displacement from the frame.

26. In a machine of the character described, in combination, a support for a gate 110 frame, mechanism for feeding cross wires to be attached to said frame, and mechanism adapted to operate upon the opposite ends of each of said cross wires to form the same 115 in a manner which will prevent their displacement from the frame, the mechanism for operating upon one end of each of said wires being electrically controlled.

27. In a machine of the character described, in combination, a support for a gate 120 frame, said frame provided with openings for the threading of wire stock therethrough, mechanism for feeding wire stock through the openings in said frame, said feeding mechanism including straightening 125 rollers, means for forming the end of the wire stock in a manner which will prevent its displacement from the frame, means for severing a wire section from the wire stock, means for retracting the wire stock to pro- 130

vide for the operation of mechanism on the severed end of the wire section, and mechanism for operating upon the severed end of said wire section to form the same in a manner which will prevent the displacement thereof from the frame.

28. In a machine of the character described, in combination, a support for a gate frame, mechanism for feeding wire stock crosswise of the gate frame, including straightening rollers and guiding means, mechanism adapted to operate on the end of the wire stock to provide a connection for the same with the frame, means for severing a wire section from the wire stock, mechanism for retracting the wire stock to provide space to be occupied by a mechanism operating upon the severed end of the section of the wire, and mechanism adapted to operate on the severed end of the wire section to provide a connection for the same with the frame.

29. In a machine of the character described, in combination, a support for a gate frame, said frame provided with openings to receive wires threaded through the frame, mechanism for feeding wire stock through the openings in said frame, including straightening rollers and guiding means, means for heading the end of the wire stock, means for severing sections of wire from the wire stock, mechanism for retracting the wire stock to provide space to be occupied by a heading means for the severed ends of the wire sections, and means for heading the severed ends of said wire sections, for the purpose of securing the wire sections to the gate frame.

30. In a machine of the character described, in combination, a support for a gate frame, said frame provided with openings to receive wires threaded through the frame, mechanism for feeding wire stock through the openings in said frame, including straightening rollers and guiding means, means for cold heading the end of the wire stock, including a member adapted to act upon the end of the wire stock and movable axially thereof, means for severing sections of wire from the wire stock, mechanism for retracting the wire stock to provide space to be occupied by a heading means for the severed ends of the wire sections, and means for hot heading the severed ends of said wire sections, including an oscillatory member adapted to move into engagement with the severed ends of the wire sections, and when heading the ends of said wire sections, occupying the space from which the wire stock is removed.

31. In a machine of the character described, in combination, a support for a gate frame, mechanism for projecting wire stock across the frame, mechanism for severing wire sections from said wire stock to provide

cross wires for the frame, a timing shaft, means for heading the ends of the wire sections, the same being controlled from said timing shaft, mechanism actuated by engagement of the end of the wire stock during the feeding thereof for setting in motion said timing shaft, the heading means for one end of said wire sections being mechanically actuated from the timing shaft, the heading means for the opposite ends of said wire sections being also mechanically actuated and including electrical connections for hot heading the ends of said wire sections when the heading means is brought into contact therewith, and means for interrupting the operation of the timing shaft during the hot heading of said wire sections.

32. In a machine of the character described, in combination, a support for a gate frame, mechanism for projecting wires across said frame, a timing shaft, mechanism actuated from the timing shaft adapted to operate upon the opposite ends of said wires for connecting the same to the gate frame, and mechanism actuated by engagement of one end of each of the wires during the feeding thereof, for setting in motion said timing shaft.

33. In a machine of the character described, in combination, a support for a gate frame, a driving shaft, mechanism actuated from said driving shaft for projecting wires across said frame, a timing shaft, clutch controlled devices for operating said timing shaft from said driving shaft, mechanism actuated from the timing shaft adapted to operate upon the opposite ends of said wires for connecting the same to the gate frame, and mechanism for actuating said clutch controlled devices, said mechanism being set in motion by engagement of one end of each of the wires during the feeding thereof.

34. In a machine of the character described, in combination, a support for a gate frame, a driving shaft, a driving member loosely carried on said shaft and adapted to have a clutch connection therewith, mechanism actuated from said driving shaft for projecting wires across said frame, a timing shaft, clutch controlled devices for operating said timing shaft from said driving shaft, mechanism for first heading one end of each of said wires and subsequently heading the opposite ends thereof, said heading mechanism being actuated from said timing shaft, mechanism for actuating said clutch controlled devices, said mechanism being set in motion by engagement of one end of each of the wires during the feeding thereof, and means for interrupting the operation of the timing shaft during the heading of one end of each of the wires.

35. In a machine of the character described, in combination, a support for a gate frame, a driving shaft, a driving member

- loosely carried on said shaft and adapted to have a clutch connection therewith, a lever and connections therewith for manually controlling the clutch connections between said driving member and said driving shaft, mechanism actuated from said driving shaft for projecting wires across said frame, a timing shaft, clutch controlled devices for operating said timing shaft from said driving shaft, mechanism for first heading one end of each of said wires and subsequently heading the opposite ends thereof, said heading mechanism being actuated from said timing shaft, mechanism for actuating said clutch controlled devices, said mechanism being set in motion by engagement of one end of each of the wires during the feeding thereof, and means for separating the clutch connection between the driving member and said driving shaft, for interrupting the operation of the timing shaft, during the heading of one of each of said wires.
36. In a machine of the character described, in combination, a support for a gate frame, a driving shaft, a driving member loosely carried on said shaft adapted to have a clutch connection therewith, mechanism actuated from said driving shaft for projecting wires across said frame, mechanism for moving said support in a step-by-step movement for advancing the gate frame through the machine to space the wires thereon, a timing shaft, clutch controlled devices for operating said timing shaft from said driving shaft, mechanism for first heading one end of each of said wires and subsequently heading the opposite ends thereof, said heading mechanism being actuated from said timing shaft, mechanism for actuating said clutch controlled devices, said mechanism being set in motion by engagement of one end of each of the wires during the feeding thereof, and means for interrupting the operation of the timing shaft during the heading of one end of each of said wires.
37. In a machine of the character described, in combination, a support for a gate frame, a driving shaft, a timing shaft, clutch controlled devices for operating said timing shaft from said driving shaft, wire feeding mechanism adapted to be actuated by the driving shaft for projecting wires across said gate frame, mechanism for heading one end of each of said wires, said mechanism including a crank shaft adapted to be operated from the timing shaft and a plunger actuated by said crank shaft which engages with the end of each of the wires for heading the same, and other means for heading the opposite ends of each of said wires, to secure the same to the gate frame.
38. In a machine of the character described, in combination, a support for a gate frame, a driving shaft, a timing shaft, clutch controlled devices for operating said timing shaft from said driving shaft, wire feeding mechanism adapted to be actuated by the driving shaft for projecting wires across said gate frame, a crank shaft and operative connections between said shaft and said timing shaft, wire clamping means operated by said crank shaft, means operated by said crank shaft for heading the clamped end of each of said wires, and other means for heading the opposite ends of each of said wires, to secure the same to the gate frame.
39. In a machine of the character described, in combination, a support for a gate frame, a driving shaft, a timing shaft, clutch controlled devices for operating said timing shaft from said driving shaft, wire feeding mechanism adapted to be actuated by the driving shaft for projecting wires across said gate frame, a crank shaft and operative connections between said shaft and said timing shaft, clamping means for the wires, cam wheels on said crank shaft and means operated thereby for actuating said clamping means, a plunger for operating upon one end of each of the wires to head the same, means operated by the crank shaft for operating said plunger, and other means for heading the opposite ends of each of said wires to secure the same, to the gate frame.
40. In a machine of the character described, in combination, a support for a gate frame, a driving shaft, a timing shaft, clutch controlled devices for operating said timing shaft from said driving shaft, wire feeding mechanism adapted to be actuated by the driving shaft for projecting wires across said gate frame, means actuated by the engagement of each of the wires when fed across the gate frame for operating said clutch controlled devices to set in operation said timing shaft, a crank shaft and operative connections between said shaft and said timing shaft, clamping means for the wires, cam wheels on said crank shaft and means operated thereby for actuating said clamping means, a plunger for operating upon one end of each of the wires to head the same, means operated by the crank shaft for operating said plunger, and other means for heading the opposite ends of each of said wires, to secure the same to the gate frame.
41. In a machine of the character described, in combination, a support for a gate frame, said frame provided with wire receiving openings, a driving shaft, a timing shaft, means for operating the timing shaft from the driving shaft, wire feeding mechanism actuated from said driving shaft for threading wires through the openings in said gate frame, a plunger for cold heading one end of each of said wires, a crank shaft

and means for operating the same from the timing shaft, means operated by the crank shaft for driving said plunger, and other means for heading the opposite ends of each 5 of said wires, to secure the same to the gate frame.

42. In a machine of the character described, in combination, a support for a gate frame, said frame provided with wire receiving 10 openings, a driving shaft, a timing shaft, clutch controlled devices for operating the timing shaft from the driving shaft, wire feeding mechanism actuated from said driving shaft for threading wires through the 15 openings in said gate frame, mechanism for operating said clutch controlled devices for setting in motion said timing shaft, said mechanism being actuated by the engagement of the ends of each of the wires when 20 the same are threaded through the frame, a plunger for cold heading one end of each of said wires, a crank shaft and means for operating the same from the timing shaft, means operated by the crank shaft for driving 25 said plunger, and other means for heading the opposite ends of each of said wires, to secure the same to the gate frame.

43. In a machine of the character described, in combination, a support for a gate 30 frame, said frame provided with wire receiving openings, a driving shaft, a timing shaft, clutch controlled devices for operating the timing shaft from the driving shaft, wire feeding mechanism actuated from said driving 35 shaft for threading wires through the openings in said gate frame, mechanism for operating said clutch controlled devices for setting in motion said timing shaft, said mechanism being actuated by the engagement 40 of the ends of each of the wires when the same are threaded through the frame, a crank shaft and means for operating the same from the timing shaft, means operated from said crank shaft for clamping one end 45 of each of said wires, means also operated by said crank shaft for cold heading the clamped end of each of said wires, and other means for heading the opposite ends of each of said wires, to secure the same to the gate 50 frame.

44. In a machine of the character described, in combination, a support for a gate frame, said frame provided with wire receiving 55 openings, a driving shaft, a timing shaft, clutch controlled gearing for operating said timing shaft from said driving shaft, wire feeding mechanism actuated from said driving shaft for threading wires through the openings in said gate frame, mechanism for 60 controlling said clutch to normally hold the timing shaft in inoperative relation to said driving shaft, and means set in motion by engagement of the end of the wire as it is fed for operating the mechanism controlling 65 the clutch to release it therefrom,

whereby the timing shaft is set in motion through the clutch controlled gearing with the driving shaft by action of and during the feeding of said wire.

45. In a machine of the character described, in combination, a support for a gate frame, said frame provided with wire receiving 70 openings, a driving shaft, a timing shaft, gearing connecting the driving shaft with the timing shaft, a clutch controlling the connection between the gearing and said timing shaft, means for normally holding said clutch in disengaged relation with said gearing, wire feeding mechanism actuated from said driving shaft for threading 75 wires through the openings in said gate frame, and mechanism for releasing said clutch holding means, said mechanism adapted to be actuated by and during the feeding of said wire. 80

46. In a machine of the character described, in combination, a support for a gate frame, said frame provided with wire receiving 85 openings, a driving shaft, a timing shaft, gearing connecting the driving shaft 90 with the timing shaft, a clutch controlling the connection between the gearing and said timing shaft, means for normally holding said clutch in disengaged relation with said gearing, wire feeding mechanism actuated 95 from said driving shaft for threading wires through the openings in said gate frame, a tensioning device for said clutch holding means actuated by said timing shaft, and means engaged by and during the feeding of 100 the wire for releasing said tensioning device, whereby clutch connection may be made between said gearing and said timing shaft to operate the latter from the timing shaft. 105

47. In a machine of the character described, in combination, a support for a gate frame, said frame provided with wire receiving 110 openings, a driving shaft, wire feeding mechanism actuated from said driving shaft for threading wires through the openings in said gate frame, a timing shaft, gearing for operating the timing shaft from said driving shaft, a clutch for controlling 115 the connection between said gearing and said timing shaft, a member for normally holding said clutch in disengaged relation with said gearing, a lever for operating said member, a tensioning device, a connection between said tensioning device and said lever, a cam on the timing shaft for operating the tensioning device, and means for operating 120 the connection between the tensioning device and said lever for releasing the member from the clutch, said operating means 125 adapted to be actuated by and during the feeding of the wire.

48. In a machine of the character described, in combination, a support for a gate frame, said frame provided with wire re- 130

51. In a machine of the character described, in combination, a support for a gate frame, said frame provided with wire-receiving openings, mechanism for threading wires through the openings in the gate frame, wire guiding and clamping means located within the confines of the gate frame, a clamping means for the end of the wire stock outside of the gate frame, means for operating said last-mentioned clamping means, means for heading the end of the wire stock held by said last-mentioned clamping means, means for severing a section of wire from the wire stock, means for operating the clamping means within the confines of the gate frame to clamp the said section of wire, and means for heading the other end of the wire section to secure the same in the frame. 80
52. In a machine of the character described, in combination, a support for a gate frame, said frame provided with wire-receiving openings, mechanism for threading wires through the openings in the gate frame, wire guiding and clamping means located within the confines of the gate frame, a clamping means for the end of the wire stock outside of the gate frame, means for operating said last-mentioned clamping means to cause it to clamp the end of the wire stock for a predetermined period of time, means for heading the clamped end of the wire stock, means for retracting the wire stock upon the release of the clamping means on the outside of the gate frame, means for severing a section of wire from the wire stock, means for operating the clamp within the gate frame to cause it to clamp the unheaded end of the wire section for a predetermined period of time, and means for heading the unheaded end of said wire section to secure the same in the frame. 95
53. In a machine of the character described, in combination, a support for a gate frame, said frame provided with wire-receiving openings, mechanism for threading wires through the openings in the gate frame, wire guiding and clamping means located within the confines of the gate frame, a clamping means for the end of the wire stock outside of the gate frame, means for operating said last-mentioned clamping means to cause it to clamp the end of the wire stock for a predetermined period of time, means for heading the clamped end of the wire stock, means for retracting the wire stock upon the release of the clamping means on the outside of the gate frame, comprising complementary fixed and movable parts, means for moving said movable parts of the guides, certain of said movable parts adapted to firmly clamp upon the wire when moved toward their complementary parts, and mechanism for forming the opposite ends of the wires to secure the same in the frame. 100
54. In a machine of the character described, in combination, a support for a gate frame, said frame provided with wire-receiving openings, mechanism for threading wires through the openings in the gate frame, wire guiding means located within the confines of the gate frame, comprising complementary fixed and movable parts, means for moving said movable parts of the guides, certain of said movable parts adapted to firmly clamp upon the wire when moved toward their complementary parts, and mechanism for forming the opposite ends of the wires to secure the same in the frame. 110
55. In a machine of the character described, in combination, a support for a gate frame, said frame provided with wire-receiving openings, mechanism for threading wires through the openings in the gate frame, wire guiding means located within the confines of the gate frame, comprising complementary fixed and movable parts, said movable parts having a hinged connection with said fixed parts of the guides, means for operating said movable parts of the guides comprising a rock shaft, connected to the movable parts of the guides. 125
56. In a machine of the character described, in combination, a support for a gate frame, said frame provided with wire-receiving openings, mechanism for threading wires through the openings in the gate frame, wire guiding means located within the confines of the gate frame, comprising complementary fixed and movable parts, said movable parts having a hinged connection with said fixed parts of the guides, means for operating said movable parts of the guides comprising a rock shaft, connected to the movable parts of the guides. 130

- tions between said rock shaft and said movable parts of the guides, a cam wheel, means for operating said cam wheel, an arm connected to the rock shaft and operated by 5 said cam wheel, and mechanism for forming the opposite ends of the wires to secure the same to the gate frame.
56. In a machine of the character described, in combination, a support for a gate frame, said frame provided with wire receiving openings, feeding rollers for feeding wire stock through the openings in the gate frame, straightening means for the wire stock, a movable support for said 10 straightening means, means for moving said support to retract the wire stock a predetermined distance after the feeding thereof, means for severing a section of wire for the gate frame from the wire stock after its 15 retraction, and means for heading the ends of the wire section.
57. In a machine of the character described, in combination, a support for a gate frame, said frame provided with wire receiving openings, feeding rollers for feeding wire stock through the openings in the gate frame, guiding means for the wire stock between said feeding rollers and said gate frame, straightening means for the wire 20 stock, a movable support for said straightening means, means for moving said support to retract the wire stock a predetermined distance after the feeding thereof, means for moving said guiding means in the 25 direction of the retraction of said wire stock, means for severing a section of wire for the gate frame from the wire stock after its retraction, and means for heading the ends of the wire section.
58. In a machine of the character described, in combination, a support for a gate frame, said frame provided with wire receiving openings, feeding rollers for feeding wire stock through the openings in the 30 gate frame, guiding means for the wire stock between said feeding rollers and said gate frame, straightening means for the wire stock, a movable support for said straightening means, an operating shaft, 35 means operated by said shaft for moving said support to retract the wire stock a predetermined distance after the feeding thereof, other means operated by said shaft for moving said guiding means in the direction 40 of the retraction of said wire stock, means for severing a section of wire for the gate frame from the wire stock after its retraction, and means for heading the ends of the wire section.
59. In a machine of the character described, in combination, a support for a gate frame, said frame provided with wire receiving openings, feeding rollers for feeding wire stock through the openings in the gate 45 frame, guiding means for the wire stock be-
- tween said feeding rollers and said gate frame, means for heading the end of the wire stock, means for retracting the wire stock subsequently to the heading of the end thereof, means for severing a wire section 50 from the wire stock, means for moving said guiding means in the direction of the retraction of said wire stock, to leave space for the movement of a heading means for the end of the wire section, a heading means for 55 the end of the wire section movable into the space occupied by said wire stock prior to the retraction thereof, and means for operating said last mentioned heading means.
60. In a machine of the character described, in combination, a support for a gate frame, said frame provided with wire receiving openings, feeding rollers for feeding wire stock through the openings in the gate frame, guiding means for the wire stock between said feeding rollers and said gate frame, an operating shaft, means operated from said shaft for retracting the wire stock a predetermined distance after the feeding thereof, other means operated by said shaft 60 for moving said guiding means in the direction of the retraction of the wire stock, means for severing a wire section from the wire stock, and means for forming the opposite ends of the wire section to secure the 65 same in the gate frame.
61. In a machine of the character described, in combination, a support for a gate frame, said frame provided with wire receiving openings, feeding rollers for feeding wire stock through the openings in the gate frame, guiding means for the wire stock between said feeding rollers and said gate frame, an operating shaft, retracting means 70 for the wire stock, comprising a movable support, a cam wheel on the operating shaft, and means operated by said cam wheel for moving said movable support, other means operated by said shaft for moving said guiding means in the direction of the retraction 75 of the wire stock, means for severing a wire section from the wire stock, and means for forming the opposite ends of the wire section to secure the 80 same in the gate frame.
62. In a machine of the character described, in combination, a support for a gate frame, said frame provided with wire receiving openings, feeding rollers for feeding wire stock through the openings in the gate frame, guiding means for the wire stock between said feeding rollers and said gate frame, an operating shaft, retracting means 85 for the wire stock, comprising a movable support, a cam wheel on the operating shaft, and means operated by said cam wheel for moving said movable support, an additional cam wheel on said operating shaft, connections between said cam wheel and said guiding means, said connections being moved 90 during the rotation of said cam wheel to 95
- 100
- 105
- 110

move said guiding means in the direction of the retraction of the wire stock, means for severing a wire section from the wire stock, and means for forming the opposite ends of the wire section to secure the same in the gate frame.

63. In a machine of the character described, in combination, a support for a gate frame, said frame provided with wire receiving openings, means for threading wire stock through the openings in said frame, means for heading the end of the wire stock, mechanism for retracting said wire stock, said retracting mechanism being momentarily interrupted, means for severing a section of wire from the wire stock during the interruption in the operation of said wire stock retracting mechanism, mechanism for heading the severed end of the wire section, said last mentioned heading mechanism operating after the completion of the operation of said retracting mechanism.

64. In a machine of the character described, in combination, a support for a gate frame, said frame provided with wire-receiving openings, means for threading wire stock through the openings in said frame, means for heading the end of the wire stock, means for clamping the end of the wire stock prior to the heading thereof and being released immediately upon the heading of the end of said wire stock, mechanism for retracting said wire stock to bring the formed head on the end thereof against the frame, said retracting mechanism being momentarily interrupted, means for severing a section of wire from the wire stock during the interruption in the operation of said wire-stock-retracting mechanism, mechanism for heading the severed end of the wire section, said last-mentioned heading mechanism operating after the completion of the operation of said retracting mechanism, and means for clamping the severed end of said wire section, said last-mentioned clamping means operating to engage said wire section just before the operation of said last-mentioned heading mechanism, and releasing said wire section immediately after the operation of said last-mentioned heading mechanism.

65. In a machine of the character described, in combination, a support for a gate frame, said frame provided with wire receiving openings, means for threading wire stock through the openings in said frame, means for cold heading the end of the wire stock, mechanism for retracting said wire stock to bring the formed head on the end thereof against the frame, said retracting mechanism being momentarily interrupted, means for severing a section of wire from the wire stock during the interruption in the operation of said wire stock retracting mechanism, mechanism for forming a hot head on

the unheaded end of said wire section, said hot-heading mechanism operating after the completion of the operation of said retracting mechanism.

66. In a machine of the character described, in combination, a support for a gate frame, said frame provided with wire receiving openings, mechanism for threading wire stock through the openings in said frame, mechanism for severing a section of wire for the gate frame from the wire stock, a header for forming a head on one end of said wire section, mechanism for actuating said hot header to move it into contact with the end of the wire section, and means for electrically heating the header when brought into contact with the wire for hot heading said wire.

67. In a machine of the character described, in combination, a support for a gate frame, said frame provided with wire receiving openings, mechanism for threading wire stock through the openings in said frame, mechanism for severing a section of wire for the gate frame from the wire stock, a header for forming a head on one end of said wire section, said header comprising a positive electrode, a negative electrode to support the gate frame through which the wire section is threaded, means for operating the header to move the same into contact with the wire section, and means for electrically heating the header, comprising a source of supply, a rotary switch, a circuit breaker, a controller, and a transformer.

68. In a machine of the character described, in combination, a support for a gate frame, said frame provided with wire receiving openings, mechanism for threading wire stock through the openings in said frame, mechanism for severing a section of wire for the gate frame from the wire stock, a driving shaft, a timing shaft, means for operating the timing shaft from said driving shaft, means for operating the severing mechanism from the timing shaft, a supplemental shaft, a header operated by said supplemental shaft for forming a head on one end of said wire section, means for rocking said supplemental shaft, means on the timing shaft for controlling the supplemental shaft, means operated by the supplemental shaft adapted when the header is brought into contact with the wire section to interrupt the operation of the driving shaft during the heading process, and means for electrically heating the header when brought into contact with the wire section for hot heading the same.

69. In a machine of the character described, in combination, a support for a gate frame, said frame provided with wire receiving openings, mechanism for threading wire stock through the openings in said frame, means for severing a section of wire

- for the gate frame from the wire stock, a driving shaft, a timing shaft, means for operating the timing shaft from said driving shaft, means for operating the severing mechanism from the timing shaft, a supplemental shaft, a header operated by said supplemental shaft for forming a head on one end of said wire section, a cam wheel on the timing shaft, an arm on the supplemental shaft, yielding means for holding the arm on the supplemental shaft against the cam surface of the cam wheel, whereby, during the rotation of said cam wheel the arm through the action of the spring is caused to follow the cam surface of the cam wheel moving the header into engagement with the end of the wire section, means operated by the supplemental shaft adapted when the header is brought into contact with the wire section to interrupt the operation of the driving shaft during the heading process, and means for electrically heating the header when brought into contact with the wire section for hot heading the same.
70. In a machine of the character described, in combination, a support for a gate frame, said frame provided with wire receiving openings, mechanism for threading wire stock through the openings in said frame, mechanism for severing a section of wire for the gate frame from the wire stock, a driving shaft, clutch controlled means for operating said driving shaft, a timing shaft, means for operating the timing shaft from said driving shaft, means for operating the severing mechanism from the timing shaft, a supplemental shaft, a header operated by said supplemental shaft for forming a head on one end of said wire section, a cam wheel on the timing shaft, an arm on the supplemental shaft, yielding means for holding the arm on the supplemental shaft against the cam surface of the cam wheel, whereby, during the rotation of said cam wheel the arm through the action of the spring is caused to follow the cam surface of the cam wheel, moving the header into engagement with the end of the wire section, means for actuating said clutch controlled means from said supplemental shaft to interrupt the operation of the driving shaft during the heading process, means for electrically heating the header when brought into contact with the wire section for hot heading the same.
75. In a machine of the character described, in combination, a support for a gate frame, said frame provided with wire-receiving openings, a driving shaft, a pair of feeding rollers for threading wires through the openings in the gate frame, a movable support for one of said rollers, means for operating said feeding rollers from said driving shaft, a timing shaft, means for operating said timing shaft from said driv-
- ing shaft, means having a predetermined 65 operation from the timing shaft for moving said movable support to separate said feeding roller, and means for manually moving said movable support to place said feeding rollers in operative relation one to the other. 70
72. In a machine of the character described, in combination, a support for a gate frame, comprising a fixed support for one side of the frame and an adjustable support for the opposite side of said frame, 75 said frame provided with wire receiving openings, mechanism mounted on that side of the machine including said fixed support for threading wires through the openings in the gate frame, mechanism mounted on that side of the machine including said adjustable support for heading one end of each of said wires, and mechanism mounted on that side of the machine including said fixed support for heading the opposite ends of 80 said wires.
73. In a machine of the character described, in combination, a support for a gate frame, said support being adjustable to receive different width frames, said frame 90 provided with wire receiving openings, mechanism for threading wires through the openings in said frame, mechanism for advancing said frame in a step-by-step movement through the machine to successively 95 present the openings in said gate frame in alignment with the wire threading mechanism, whereby wires may be successively threaded through the openings in said frame, and means for forming the opposite 100 ends of the wires to secure the same to the frame.
74. In a machine of the character described, in combination, a support for a gate frame, said frame provided with wire-receiving openings, mechanism for threading wires through the openings in said frame, rack-bars connected with said support, an operating shaft, a supplemental 105 shaft, gearing connecting said supplemental shaft with said rack-bars, means for rotating said supplemental shaft in a step-by-step movement from said operating shaft, to successively present the openings in said frame in alignment with said wire-threading mechanism, means for manually rotating said supplemental shaft to move said support for preliminarily positioning said gate frame relative to said wire-threading mechanism, and means for forming the opposite ends of said wires to secure the same 110 to the gate frame.
75. In a machine of the character described, in combination, a support for a gate frame, said frame provided with wire-receiving openings, mechanism for threading wires through the openings in said frame, rack-bars connected with said sup-

port, an operating shaft, a supplemental shaft, gear wheels carried on said supplemental shaft in mesh with said rack-bars, a ratchet wheel on said supplemental shaft, a lever on said supplemental shaft, a pawl pivotally connected with said lever and

adapted to engage with the teeth on said ratchet wheel, means for operating said lever from said operating shaft, and means for heading the opposite ends of said wires 10 to secure the same to the frame.

WILLIAM H. SOMMER.
